UNITED STATES PATENT OFFICE.

LEWIS GEISERT, OF NEW YORK, N. Y.

DESIGN FOR A COLLAR-BUTTON.

SPECIFICATION forming part of Design No. 34,020, dated February 5, 1901.

Application filed December 1, 1900. Serial No. 38,375. Term of patent 3½ years.

To all whom it may concern:

Be it known that I, LEWIS GEISERT, a citizen of the United States, residing at New York, (Brooklyn,) in the county of Kings and State of New York, have invented and produced a new and useful Design for Collar-Buttons, of which the following is a specification.

My invention is a design for collar-buttons; and it consists in the novel shape and configuration hereinafter described, and illustrated in the accompanying drawings, which form a part of this specification, and in which—

Figure 1 is a view in perspective of a collar-button embodying my design. Fig. 2 is a top plan view of the same. Fig. 3 is a transverse section of the head of the button.

The reference numeral 1 designates the shank of the button, and 2 the base thereof, the latter being of circular or disk form.

3 designates the head of the button of general elliptical form, its sides being rounded, as shown in Fig. 2, and having an upwardly-projecting end extension 4, terminating in a

ball 5. The under surface 6 of the head is slightly rounded in cross-section, as best shown in Fig. 3, and its upper surface 7 is of convex form. The under surface of the head is also rounded longitudinally, so that the under surface of the end 8 and the under surface 9 of the extension 4 are above the horizontal plane of the central portion of the head.

The leading feature of the design is the head 3, having its sides rounded, as shown, to impart an elliptical shape thereto and provided with the end extension and being of rounded and convex shape in cross-section.

I claim—

The design for a collar-button herein shown and described.

In testimony whereof I affix my signature in presence of two witnesses.

LEWIS GEISERT.
